UNITED STATES PATENT OFFICE.

EDSON B. CARD, OF NEW YORK, N. Y.

DESIGN FOR A DOLL.

Application filed June 12, 1922. Serial No. 2,631. Term of patent 7 years.

To all whom it may concern:

Be it known that I, EDSON B. CARD, a citizen of the United States, residing in the city of New York, borough of Manhattan, in the county of New York and State of New York, have invented a new, original, and ornamental Design for a Doll, of which the following is a specification, reference being had to the accompanying drawing, forming part thereof.

The drawing shows a perspective view of the doll.

I claim:

The ornamental design for a doll, as shown.

EDSON B. CARD.
